INVENTOR,
Maud M. Gillette,
BY
Henry J. Lucke,
ATTORNEY.

UNITED STATES PATENT OFFICE

MAUDE M. GILLETTE, OF NEW YORK, N. Y.

SUPPORT FOR PICTURES, CARDS, ETC.

Application filed October 25, 1927. Serial No. 228,524.

My invention relates to simple and inexpensive devices for supporting cards, pictures and the like on walls or other upright surfaces.

5 The general object is to provide devices of this character which are extremely simple and may therefore be cheaply produced, are strong and durable, are easily inserted in a wall or other support, and in which the card 10 or picture may easily be inserted without any injury to it or positive mechanical connection to the supporting devices.

To realize these and other objects, the supporting device in a representative embodiment, as here shown, is preferably formed 15 from a single small sheet of substantially stiff, bendable metal, cut and bent to provide a prong and a card-holding portion in generally transverse relation to the prong, said 20 card-holding portion being arranged either to engage only the end and bottom edges of the card at the corner thereof, and the outer card face, or to additionally engage the inner face of the card; and in either case serving 25 by the cooperative action of two of the devices at opposite lower corners of the card to retain the same securely but removably in upright position, close to or in contact with the wall surface.

30 The characteristics and advantages of the invention are further sufficiently explained in connection with the following detail description of the accompanying drawings, which illustrate certain representative embodiments. After considering these examples, skilled persons will understand that many variations may be made without departing from the principles involved, and I 35 contemplate the employment of any structures that are properly within the scope of the appended claims.

Fig. 1 is a perspective view of devices embodying the invention in one form, in operative position.

45 Fig. 2 is a left side view at 2—2, Fig. 1,

the wall or analogous supporting body being shown in section.

Fig. 3 is a rear perspective of one of the supporting devices of Figs. 1 and 2.

Fig. 4 is a plan view of the blank from 50 which the supporting device of Fig. 3 is produced.

Fig. 5 is a perspective view of a modified form.

Fig. 6 is a top plan view of one of the devices in operative position. 55

Fig. 7 is a plan view of the blank from which the device of Fig. 5 is produced.

Fig. 8 is a perspective view of another modification. 60

Fig. 9 is a plan view of the blank from which the device of Fig. 8 is produced.

Referring first to Fig. 4, I produce from sheet metal of moderate thickness and of substantial stiffness, and of proper composition and temper to permit the necessary pressing or bending operations, a blank B including generally rectangular portions or wings 1 and 2, and a prong portion 3 having a bevelled or tapered point 4. Desirably the 70 upper portions of the wings are separated by a notch formation producing on wing 2, a margin 5 aligned with the prong, and on wing 1, a diagonal margin 6; although in some cases the separation of these wing portions 75 may consist of a simple slit aligned with the prong, as later described with reference to Figs. 8 and 9. The blank is to be bent along the dotted lines, of which *a* indicates flange portions 7 and 8 to cooperate with the card 80 edges, and *b* indicates central bending of the prong, after which the prong is twisted into tapering, sharp-pointed form.

Fig. 3 shows the completed support or holder after performance of the stated operations. The flange members 7 and 8 are located in planes perpendicular to each other extending from the base of prong 3, which is now in the tapered and pointed form referred to, while wing portions 1 and 2 extend in sub- 90

stantially the same plane but in overlapping relation, at right angles to the flanges 7 and 8. Edge 6 extends from the corner of the support (or from a point adjacent the base of the prong) diagonally to the inward vertical edge of wing 2, which it overlies, this arrangement or appearance of the edge 6 being mainly for decorative effect.

Figs. 1 and 2 show two of the devices in operation. The prongs are inserted usually merely by pushing (although they may be hammered if necessary) into a wall or other supporting body *W*, and with the lower corners of a picture or card *C* inserted in the sockets provided by the holders, the lower edges of the card resting in the one case on flange 7 and in the other case on flange 8 while the vertical edges of the card are engaged by the other respective flanges, which prevent lateral movement of the card. The outer face of the card is engaged by the wings 1 and 2 which contact with sufficient card areas to hold the same firmly in upright position, flat against the wall or other supporting surface. It is now apparent that the described mode of construction obviates any necessity for making the device in "rights" and "lefts", and that the same device may be used for either corner of the card by merely turning it to proper position. The diagonal edges 6 in each instance are directed substantially toward the center of the card and present an attractive appearance analogous to the mitre joints of picture frames and the like.

It will be evident that the holders may be used to support a great variety of articles including practically any heavy cards, or pictures mounted on cards or cardboard frames, etc.

Figs. 5, 6 and 7 show a modification in which the blank *B*¹ of Fig. 7 comprises in addition to the parts of the blank *B*, wing formations 10 and 11, the inward ends of which are separated from the prong 3 by slits 12, and the longitudinal inward edges are defined by the dotted lines *c*. When this blank is bent and otherwise operated upon as previously explained, all of its parts as shown in Figs. 5 and 6 are substantially as in the previous example, and the wing formations 10 and 11 are located to engage inner faces of the card corner; or in brief the device provides a four-sided socket engaging the bottom and end edges of the card as well as its inner and outer faces at the corners; and when in use as sufficiently shown in Fig. 6, firmly and stiffly supports the card or picture in vertical position, but spaced slightly from the wall surface. In either example it will be noted that the cards may be readily inserted and removed from their holders without detaching the latter from the wall.

Figs. 8 and 9 show another modification in which the blank *B*² of Fig. 9 is generally similar to that of Fig. 7 except that it is of

more nearly square outline, and the angular edge 6 of Figs. 4 and 7 is dispensed with, the separation of wing portions 1 and 2 consisting merely of a slit 15 aligned with the prong 3. This blank is bent up substantially as in the previous example, producing as shown in Fig. 8 a holder or socket of substantially square face outline.

While these devices are conveniently and economically produced from sheet metal, other materials may be used in some cases and in the broader aspects of the invention it is not limited as to the particular material employed, and in fact many other variations may be made without departing from the principles disclosed.

It will be observed that in the use of my invention there is no need for any positive mechanical connection between the holder and the picture or similar article and therefore no necessity for in any way marring the picture or card, as is the case when thumb-tacks, push-pins or other pointed devices are inserted through the card corners.

I claim:

1. A support or holder of the class described comprising a socket portion including card-edge engaging members extending at right angles to each other, card face engaging members extending perpendicularly to the edge members and parallel to each other, said card face engaging members overlapping one another and a pointed prong extending from the intersection of said edge engaging portions and at a right angle to the card-face engaging members.

2. A support or holder of the class described comprising a socket portion including card-edge engaging members extending at right angles to each other, card face engaging members extending perpendicularly to the edge members and parallel to each other, said card face engaging members overlapping one another and a twisted and tapered prong extending from the intersection of said edge engaging portions and at a right angle to the card-face engaging members.

3. A blank for the production of a support or holder of the class described, consisting of bendable sheet material and comprising wing portions, and a prong extending at a right angle from the intersection of the wing portions, the adjacent ends of the wing portions being separated substantially in line with the prong, and the inward edge of one of the wing portions being cut diagonally.

4. A blank for the production of a support or holder of the class described, consisting of bendable sheet material and comprising wing portions, and a prong extending at a right angle from the intersection of the wing portions, the adjacent ends of the wing portions being separated substantially in line with the prong, and additional wing portions

at opposite sides of the prong and separated therefrom.

5. A blank for the production of a support or holder of the class described, consisting of a foldable sheet material and comprising wing portions, and a prong extending at a right angle to the intersection of the wing portions, the fold line between the wing portions being in alignment with said prong, said blank being folded along a line transverse to said fold line.

In testimony whereof I have signed this specification this 22nd day of October, 1927.

MAUDE M. GILLETTE.
